Atty's.

UNITED STATES PATENT OFFICE.

SAMUEL I. SUTTON, OF DUBLIN, VIRGINIA.

SASH-HOLDER.

SPECIFICATION forming part of Letters Patent No. 224,363, dated February 10, 1880.

Application filed December 23, 1879.

To all whom it may concern:

Be it known that I, SAMUEL I. SUTTON, of Dublin, in the county of Pulaski and State of Virginia, have invented certain new and useful Improvements in Sash-Holders; and I do hereby declare that the following is a full, clear, and exact description of the invention, which will enable others skilled in the art to which it appertains to make and use the same, reference being had to the accompanying drawings, which form a part of this specification.

Figure 1 is a front view. Fig. 2 is a vertical section on line *x x*, Fig. 1; and Fig. 3 is a vertical section on line *y y*, Fig. 2.

Corresponding parts in the several figures are denoted by like letters of reference.

This invention relates to sash-holders; and it consists in certain improvements in the construction of the same which will be herein-after fully described, and particularly pointed out in the claim.

In the annexed drawings, A represents the frame or casing, and B B the sashes, of an ordinary window.

My improved holder consists of a bail or bracket, C, in which an eccentric disk, D, provided with a suitable handle, E, is journaled upon a screw or some other suitable pivot, F. The handle E and outer edge of the eccentric are provided with a transverse slot, G, forming a continuation of an annular groove, H, extending around the periphery of said disk, and a set-screw, I, inserted through a threaded perforation in the outer edge of the eccentric, bears toward the bottom of said annular groove.

J is a narrow strap, of rubber, rubber cloth, or other suitable material, which passes through slot G and around disk D, in the groove of which it is fitted in such a manner

as to project slightly beyond the periphery of 40 said disk, the ends of strip J being secured by the set-screw I.

In operation the eccentric disk D does not interfere with the raising of the sash; but when the hold upon the sash is released the 45 weight of handle E or pressure exerted upon the latter will force the eccentric against the side of the window-frame, thereby creating sufficient frictional resistance to support the sash at the point to which it has been raised. 50 By lifting the handle the eccentric is withdrawn and the sash may be lowered.

The band J, which is for the purpose of preventing the sash from slipping, may, when worn out, be easily replaced by removing or 55 loosening the screw I.

I am aware that elastic bands, in combination with eccentric cams or disks, are not new in sash-holders. Such, therefore, I do not broadly claim; but,

Having thus described my invention, I claim and desire to secure by Letters Patent of the United States—

As an improvement in sash-holders, the eccentric disk D, having handle E, slot G, annular groove H, set-screw I, and friction-strap J, in combination with the bail or bracket C, having pivot F, the whole arranged and operating substantially as and for the purpose herein shown and specified.

In testimony that I claim the foregoing as my own I have hereto affixed my signature in presence of two witnesses.

SAMUEL INGRAM SUTTON.
